BACON HANGER

John E. Covey, Harrisburg, Pa., assignor to Industrial Patents Corporation, Chicago, Ill., a corporation of Delaware

Application August 20, 1932, Serial No. 629,675

9 Claims. (Cl. 17—44)

The invention relates to a bacon hanger. The object of the present invention is to improve the construction of bacon hangers and to provide a simple, practical and efficient bacon hanger of the comb clamp hanger type adapted to be readily applied to skinned and unskinned bacon bellies, wherein the side support is placed upon the lever supporting side of the hanger rather than on the hook side whereby the weight of the bacon belly will securely maintain the hanger clamp in engagement with the bacon belly.

A further object of the invention is to provide a comb clamp bacon hanger of this character capable of automatically adjusting itself to a bacon belly as the latter shrinks, whereby the upper engaged end of the belly will be securely clamped and maintained in proper position at all times.

With these and other objects in view, the invention consists in the construction and novel combination and arrangement of parts herein-after described, illustrated in the accompanying drawings, and set forth in the claims hereto appended, it being understood that various changes in the form, proportion, and minor details of construction, within the scope of the claims, may be resorted to without departing from the spirit of the invention or sacrificing any of the advantages thereof.

In the drawings:

Figure 1 is a perspective view of a comb clamp bacon hanger constructed in accordance with this invention and shown applied to a slab of bacon.

Fig. 2 is a front elevation of the same.

Fig. 3 is an end view of the comb hanger applied to a slab of bacon.

Fig. 4 is a vertical sectional view on the line 4—4 of Fig. 2.

Fig. 5 is a perspective view of a comb bacon hanger shown applied to a slab of bacon and illustrating another form of the invention.

Fig. 6 is a front elevation of the same.

Fig. 7 is an end view of the comb bacon hanger shown in Figs. 5 and 6.

Fig. 8 is a vertical sectional view on the line 8—8 of Fig. 6.

Referring particularly to Figs. 1 to 4 inclusive of the drawings, in which is illustrated one form of the invention, a comb bacon hanger which is adapted to be applied to either skinned or unskinned bellies or slabs of bacon is illustrated in the said figures applied to a slab 1 from which all 55 of the skin has been removed with the exception

of a narrow strip 2 which extends across the upper end of the slab. The comb clamp hanger comprises in its construction a substantially oblong frame composed of an upper rear horizontal pivot rod 3 and a lower front horizontal rod 4 connected at its terminals with the pivot rod 3 by substantially sigmoidally bent ends 5. The said oblong frame is preferably constructed of a single piece of rod metal or other suitable material and the lower front horizontal rod which constitutes a bacon engaging jaw is provided at intervals with inclined inwardly and upwardly extending pointed teeth or prongs 6 adapted to readily penetrate the strip 2 of skin and be embedded in the same. The strip 2 of the bacon skin has its upper marginal edge portion 2^a partially severed from the bacon and the teeth or prongs 6 pierce the partially severed portion of the skin and enable the clamp to securely engage and support the bacon without liability of mutilating or otherwise injuring the meat. The sigmoidal ends 5 which form oppositely extending loops 7 and 8 in addition to connecting the pivot rod 3 and the jaw 4 form closures for the ends of the hanger and rearwardly offset the pivot rod 3 from the vertical plane of the jaw 4.

The pivot rod forms a fulcrum for a clamping lever constructed of rod metal or other suitable material which is coiled at spaced points at the ends of the hanger at 9 to form coils which constitute bearing eyes for the clamping lever. The pivot rod 3 passes through the coils 9 and the clamping lever is composed of a depending arm 10 and a forwardly extending approximately U-shaped arm 11 which is provided with an upwardly extending suspension hook 12. The depending arm 10 is composed of vertical end portions and a pair of spaced horizontal rods 13 preferably of a diameter less than the diameter of the metal of the body portion of the clamping lever and constituting a jaw for cooperating with the jaw 4 to clamp the upper end of the slab of bacon.

A hook 12 is preferably formed by twisting the metal of the clamping lever to form a stout shank 14 and a curved bill or engaging portion. The suspension hook is located at one side of the center of the clamping lever and is in an off-center position, whereby a square shape is secured as the contraction of the belly side in smoking is greater than that of the back side and by hanging the bacon slightly offcenter the said unequal contraction is counteracted and a square shape is obtained.

The comb clamp hanger is adapted to be easily

and quickly applied to a slab of bacon and when applied to the meat and subjected to the weight thereof, the weight of the meat will draw the clamping lever and the jaw of the frame, which is pivotally connected with the clamping lever, into proper clamping position on the meat as long as the same is suspended in the hanger.

As the meat shrinks the clamp will properly adjust itself to the meat so that the upper end 10 of the slab or belly will always be held in proper position.

In Figs. 6 to 8 inclusive, is illustrated another form of the invention in which the substantially oblong frame 15 is provided with approximately 15 inverted L-shaped end prongs 16 connecting the upper rear pivot rods 17 with the lower front rod 18. The lower front horizontal rod 18 which forms a jaw is provided with pointed inclined teeth or prongs 19 extending upwardly and inwardly from the jaw and adapted to penetrate the slab of bacon. The approximately inverted L-shaped ends 16 consists of upper horizontal portions and depending vertical portions which offset the pivot rod 17 rearwardly from the vertical 20 plane of the jaw 18.

The horizontal pivot rod 17 has mounted on it a lever 20 constructed substantially the same as that heretofore described and comprising a forwardly extending approximately U-shaped arm 30 and a depending approximately vertical arm and provided at the angle formed by the arm with coils 21 constituting bearing eyes and arranged on the pivot rod 17. The depending arm of the clamping lever is composed of vertical ends 22 35 and spaced parallel horizontal rods 23 of a diameter less than the diameter of the metal of the body portion of the lever. The horizontal rods 23 form a jaw for engaging the slab of bacon and they cooperate with the jaw 18 in firmly 40 engaging and supporting the slab of bacon.

The horizontal portions of the inverted L-shaped arm 16 close the end of the hanger at the top and the ends 22 of the depending arm of the hanger are provided with forwardly extending 45 approximately triangular loops 24 formed integral with the ends 22 and arranged transversely of the hanger and constituting closures for the lower portions of the ends of the hanger.

The forwardly extending approximately U-shaped arm of the clamping lever is provided 50 with a hook 25 having a twisted shank 26 and located at one side of the center of the hanger similar to the suspension hook heretofore described.

55 What is claimed is:

1. A bacon hanger comprising a frame provided with a jaw and a pivot rod, and a clamping lever fulcrumed on the pivot rod and having a clamping member to cooperate with the said jaw, positioned substantially opposite thereto, said clamping lever being provided with hanger suspension means.

2. A bacon hanger comprising a frame provided with a jaw and a pivot rod, and a clamping lever fulcrumed on the pivot rod provided with a clamping member to cooperate with the said jaw, positioned substantially opposite thereto and provided with an approximately U-shaped upper arm extending from the pivot rod at substantially a right angle to said clamping member to avoid contact with the bacon and provided with hanger suspension means.

3. A clamp hanger of the class described comprising a frame of approximately oblong form 75 composed of a bottom front longitudinal rod

forming a jaw, an upper rearwardly offset longitudinal pivot rod and ends connecting the terminals of the jaw and the pivot rod, and a clamping lever fulcrumed on the pivot rod and having a depending clamping member to cooperate with the said jaw and positioned substantially opposite thereto and provided with an upper arm extending forwardly from the pivot rod and having hanger suspension means.

4. A clamp hanger of the class described comprising a frame of approximately oblong form composed of a lower front longitudinal rod forming a jaw, an upper rearwardly offset longitudinal pivot rod and substantially sigmoidally shaped ends connecting the terminals of the jaw and the pivot rod and forming closures for the ends of the hanger, and a clamping lever fulcrumed on the pivot rod and having a depending clamping member to cooperate with the said jaw and provided with an upper arm extending forwardly from the pivot rod and provided with hanger suspension means.

5. A clamp hanger of the class described comprising a frame having a lower front jaw and provided with an upper rearwardly offset pivot, 100 and a clamping lever fulcrumed on the frame by the said pivot and provided with a substantially vertical depending clamping member to cooperate with the said jaw and having an upper approximately U-shaped arm extending forwardly 105 from the said pivot and provided with hanger suspension means, said clamping member comprising two rods, said jaw being positioned opposite said clamping member in a plane between said rods.

6. A clamp hanger of the class described comprising a frame of approximately oblong form composed of a lower front longitudinal rod forming a jaw, an upper rearwardly offset longitudinal pivot rod and substantially sigmoidally shaped 115 ends connecting the terminals of the jaw and the pivot rod and forming closures for the ends of the hanger, and a clamping lever fulcrumed on the pivot rod and having a depending approximately vertical clamping member to cooperate with the said jaw, positioned opposite thereto and provided with an upper approximately U-shaped arm extending forwardly from the pivot rod and provided with an integral upwardly extending suspension hook.

7. A clamp hanger of the class described comprising a frame of approximately oblong form composed of a lower front longitudinal rod forming a jaw, an upper rearwardly offset pivot rod and an approximately inverted L-shaped end 130 connecting the terminals of the pivot rod and the said jaw, and a clamping lever fulcrumed on the pivot rod and provided with a depending clamping rod cooperating with the said jaw, positioned opposite thereto and having at its terminals forwardly extending transversely disposed loops forming closure portions for the ends of the hanger.

8. A clamp hanger of the class described comprising a frame of approximately oblong form 140 composed of a lower front longitudinal rod forming a jaw, an upper rearwardly offset pivot rod and approximately inverted L-shaped ends connecting the terminals of the pivot rod and the said jaw, and a clamping lever provided with a depending approximately vertical clamping member cooperating with the said jaw, positioned opposite thereto and having approximately V-shaped end loops disposed transversely of the hanger, and forming closure members for the same, said 145

clamping lever being also provided with an upper approximately U-shaped arm extending forwardly from the pivot rod and provided with hanger suspension means.

5 9. A clamp hanger of the class described comprising a frame of approximately oblong form composed of a lower front rod forming a jaw and an upper rearwardly offset pivot rod connected at its terminals with the ends of the jaw,

and a clamping lever having spaced coils arranged on the pivot rod whereby the clamping lever is fulcrumed thereon, said clamping lever having a depending clamping member to cooperate with the jaw, positioned opposite thereto and provided with a forwardly extending arm having suspension means located approximately in a vertical plane of the jaw of the frame.
